UNITED STATES PATENT OFFICE.

BENJAMIN DOUGLAS THOMAS, OF ITHACA, NEW YORK, ASSIGNOR OF ONE-TENTH TO THOMAS-MORSE AIRCRAFT CORPORATION, OF ITHACA, NEW YORK, A CORPORATION OF NEW YORK.

AIRPLANE WING CONSTRUCTION.

Application filed March 8, 1923. Serial No. 623,613.

This invention relates to the construction of wings for airplanes, either monoplanes or biplanes, and has for one of its objects to improve the pilot's vision without diminishing the wing area, while at the same time maintaining the full aerofoil section substantially the same throughout the span of the wing.

With the usual straight wing construction as heretofore used, the point of the pilot's vision is located very near the rear or trailing edge of the wing, with the result that a large angle of vision is obstructed by the full depth of the chord being so near the pilot. According to my improvement, the middle portion of the wing is extended forward, thus bringing the maximum chord depth farther from the pilot and greatly diminishing the obstructed angle. As both the leading edge and the trailing edge are set forward, the aerofoil section remains of substantially the same width throughout, and is not weakened by cutting or reducing the wing area.

Another feature of my improvement comprises trussed metal wing beams with a covering of sheet metal having the sections overlapping and riveted to the wing beam flanges thereby preventing the rivets from shaking or vibrating loose. The nose portion of the wing is also formed in one piece, of a sheet of metal bent around with its ends riveted to the top and bottom flanges of the forward beam.

In the accompanying drawing: Figure 1 is a plan, in diagram, showing a form of wing embodying my improvement; Fig. 2, an end elevation of the same; Fig. 3, a sectional outline, indicating the aerofoil section at the centre, line 3—3, of the wing, Fig. 4, a front elevation; Fig. 5, a perspective view, showing a section of improved wing construction; and, Fig. 6, an enlarged detail section of a wing beam.

As shown in the drawing, the portion, 7, of the wing above the cock pit, 8, which is usually the middle portion of the wing, is extended forward both at the leading edge, 9, and the trailing edge, 10, of the wing, whereby the aerofoil section in the extended middle portion is substantially the same as at the side portions, so that the same aerofoil section is maintained throughout the span of the wing without cutting or reducing

the wing area. By this means the maximum depth of chord is advanced some distance 55 from the point, 11, indicating the eye of the pilot in the cock pit, whereby the obstructed angle of vision is much smaller than in the case of the usual straight wing having parallel leading and trailing edges. This is indicated by the dotted lines in Figs. 2 and 3. The middle portion of the wing is also preferably raised slightly above the level of the side portions, as indicated in the front elevation, Fig. 4.

According to another feature of my improvement, the wing beams, 14, are formed of trussed metal sections, and the covering is composed of metal, such as duralumin, formed in sheets, preferably corrugated, and of the proper length to overlap at their adjoining ends at the wing beams, said overlapping ends being riveted to the wing beams. The beam flanges may be constructed of double angle sections, 12, riveted back to back, with a cap strip, 13, on the top, as shown in Fig. 6. The web members, 17, may be made up of single or multiple corrugated metal strips. The ends of the corrugated metal sheets, 15, forming the covering, overlap and are riveted to the flanges, 12, of the wing beams, as indicated, thereby forming a strong and durable joint, and one in which the rivets will not shake loose. The nose portion of the wing comprises a single metal sheet, 16, bent around to the proper form, and having its edges riveted to the top and bottom flanges, respectively, of the forward beam.

As indicated in Fig. 1, the main wing beams, 14, indicated in dotted lines, extend longitudinally of the wing, and substantially parallel, while auxiliary wing beams, 18, extending at an angle to the main wing beams, may be provided for the middle or forwardly extended portion.

This construction of wing with the forwardly extending middle portion, also has the advantage that the centre of lift of the wing is brought further forward without producing any structural disadvantage.

Having now described my invention, what I claim as new and desire to secure by Letters Patent is:

An airplane wing of full aerofoil section 105 throughout its span and shaped so as to in-

crease the pilot's angle of vision without diminishing the wing area, the middle portion of the wing being extended forward for said purpose at both the leading and trailing edges, parallel transverse trussed beams in the side portions of the wing, and auxiliary beams, of similar construction, in said mid-

dle portion, said auxiliary beams being arranged at an angle to said side portion beams and connected thereto.

In testimony whereof I have hereunto set my hand.

10

BENJAMIN DOUGLAS THOMAS.
